METHOD OF PREPARING SUBGRADES FOR
ROADS AND HIGHWAYS

Prevost Hubbard, White Plains, N. Y.

Application March 17, 1930, Serial No. 436,525

4 Claims. (Cl. 94—22)

My invention consists in the novel features hereinafter described, reference being had to the accompanying drawing which illustrates an embodiment of my invention selected by me for 5 purposes of illustration, and a slight modification thereof, and said invention is fully disclosed in the following description and claims.

The efficiency of any road or highway must depend, to a greater or less extent, upon the 10 support afforded by the subgrade or natural soil upon which the roadway proper rests. The major problem which soil subguards for highways presents is the variation in moisture content. Most dry soils, when properly compacted, 15 will sustain the loads to which highways are subjected, so long as they can be maintained free from excess moisture. Water finds its way into subgrade soil mainly by

1. Direct precipitation,
- 20 2. Run off and side infiltration
3. Capillary rise from accumulation of water which may be drawn upward into the upper portions of the subgrade from depths very considerably below the surface.
- 25 The provision of a waterproof wearing surface and the installation of adequate drains and culverts will serve to protect the subgrade against the infiltration of water from the first two or of these sources, but will have no effect what-
- 30 ever in preventing the saturation of the subgrade with excess water by capillary action from below, which, especially at certain periods of the year, or by frost action, frequently softens the subgrade material to such an extent as to
- 35 cause failure of the entire road structure carried upon it under traffic loads.

In an attempt to prevent the breaking down of the road structure locally, due to excess moisture drawn into the subgrade soil by capillary 40 action, it has been deemed necessary in the more important highways to adopt a pavement of such thickness and character as to support the traffic loads even when the subgrade soil contains the maximum excess of water due to 45 capillary action. This often involves enormous expense of initial construction throughout the entire length of the road or highway, and even such roads may fail at certain points where unusual or unexpected quantities of water are 50 drawn into the subgrade soil by capillary action. Obviously such expensive types of highways are 55 inapplicable to thousands of miles of roads which must be maintained, and where the provision of adequate funds for the more expensive types of road construction is impracticable.

My invention, which relates to the method of building a road, pavement, path, airport runway, taxiway, landing strip or field, has for its object to provide below a pavement or roadway, etc., a layer of natural subgrade soil of sufficient depth to support the traffic loads, to which the road is subjected, when in moderately dry and compact condition, and to prevent the rise of moisture by capillary action to said layer by interposing between it and the body of soil below, an impervious septum which will prevent the access of water thereto by capillary action, the said dry compact layer of subgrade material being further protected from moisture of precipitation by a water-proof wearing surface or 60 pavement, and from side infiltration by proper drains or ditches, so constructed that the level of water therein shall be below the level of the septum. In some instances, where it may be 65 found necessary or desirable, a plurality of impervious septums may be employed at different distances below the upper surface of the final subgrade soil, in which case the water level of the drainage ditches will ordinarily be below 70 the lowest septum, but for ordinary road construction, and especially for firm roads and the like, a single septum below a layer of dry compact subgrade soil of suitable depth will be 75 sufficient.

In carrying out my invention, it will be obvious that the surface treatment, that is to say, the actual pavement or roadway which protects the subgrade layer from moisture of precipitation and supplies the necessary surface wearing course, to prevent indentation by the wheels of 85 vehicles, may be comparatively thin since the traffic loads are supported directly by the subgrade material itself, and the cost of road structure is thereby vastly decreased. It is to be understood, however, that my invention is also 90 applicable to the more expensive types of road as it will not only relieve them from the present menace of accumulation of water in the subgrade soil by capillary action, but will permit 95 of the use of a pavement of less depth, and greatly decrease the cost of building the more expensive types of roadways, such for example, as those of concrete, cement, or other like construction, and those composed of granular stone combined with asphalt, or other binders, also 100 brick and block.

Referring to the accompanying drawing, which 105 illustrates one manner in which my invention may be carried into effect, and a slight modification thereof,

Fig. 1 represents a cross section of the sub-grade for a road or highway prepared in accordance with my invention.

Fig. 2 represents the same subgrade construction, with a relatively thin wearing course or pavement of waterproof character thereon.

Fig. 3 represents a slight modification of my invention in which a plurality of impervious septums below the dry compact subgrade layer are shown.

In carrying my invention into effect, a surface of natural soil, indicated at 1, is prepared, represented by the dotted line, $x-x$, in Figs. 1 and 2, at a predetermined distance below the upper level of the subgrade soil material upon which the pavement or roadway proper is to be constructed. This will ordinarily be accomplished by excavating the roadway to the required depth and removing the natural subgrade material therefrom, but obviously where filling is necessary, the level indicated by the dotted line, $x-x$, must be obtained in the usual manner. Upon the surface of the soil, 1, at the level indicated by the dotted line, $x-x$, I provide an impervious septum, which is indicated at 2, extending over the entire surface beneath the roadway, and between the drainage ditch, indicated at 3, with which the subgrade is to be provided. I have found that capillary rise of water in soils of high capillary action can be checked by a relatively thin layer of bituminous material, or soil mixed with or impregnated with bituminous material, and under ordinary circumstances the impervious septum, 2, may be provided in this manner. For example, I may employ a cheap grade of asphaltum road oil, such as is commonly used for the surface treatment of earth roads, but I may use other bituminous compounds with or without admixture to soil or other materials. My invention, however, includes any type of impervious septum which will prevent the rise of water therethrough by capillary action, such as impervious sheet material of any kind which will not become disintegrated by the action of the surrounding earth. Suitable sheet material provided with a protecting coating on one or both sides to insure against disintegration or to render it impervious may also be employed, but as one of the objects of my invention is to provide an exceedingly inexpensive and yet durable and satisfactory roadway, I prefer to employ a septum composed mainly or entirely of bituminous material, or such material mixed with soil or other granular material. The dry subgrade material, indicated at 4, is superimposed upon the septum, 2, to the desired depth. If the level, indicated by the dotted line, $x-x$, has been obtained by removing the subgrade material, this same material may be replaced and the drainage ditches, 3, are provided of such depth that the normal water level therein will not at any time rise above the level of the septum, 2. The depth of the dry subgrade material, 4, which will ordinarily be of exactly the same character as the soil, 1, below the septum, will depend upon the character of the subgrade soil. Ordinarily the subgrade material will be replaced above the septum, 2, in exactly the same condition in which it was before its removal. Obviously, however, in some instances, additions of sand or clay may be made, if desired, but this will not ordinarily be necessary. The dry subgrade material will be graded and compacted in any ordinary or preferred manner, with or without the addition of water, and the shoulders, indicated at 4^a, will

preferably be given a sufficient inclination toward the respective drainage ditches, to facilitate drainage of precipitated moisture. This dry compact subgrade material is then covered with a road surface, or pavement, which preferably should be of a water-proof character. In Fig. 2, for example, I have shown a thin road surface, indicated at 5, which may be composed of bituminous material, with or without finely divided stone or other suitable material, and all in desired depth. The shoulders, 4^a, may also be coated with water-proof material, as indicated at 5^a, if desired, although when properly constructed and given the requisite inclination toward the drainage ditches, little infiltration is to be feared from this source. In the finished roadway, the wearing course or finished pavement, whatever its character may be, is supported upon a substantially thick subgrade material composed of reasonably dry compact sub-grade soil, beneath which is an impervious septum extending the full width of the roadway, between the side ditches or drains, but at an elevation above that of any standing water that might be expected to accumulate within them. The dry compact subgrade material, 4, is therefore protected from capillary moisture in the earth, 1, below it by the impervious septum, 2, and is further protected from accumulation of excess water or precipitation or lateral infiltration so that it will remain through the seasons in the same condition, and will at all times provide the necessary support for road traffic.

It will be understood that the dry subgrade material so protected from excess moisture in all directions, including infiltration from the bottom by capillary action, forms no part of the pavement of the roadway, whether comprising merely an impervious surface treatment of comparatively little thickness, or a thicker strata including what may be termed foundation material surmounted by an impervious surface wearing course, all of which if used will be located above and rest upon the dry subgrade material so protected against moisture.

The depth of the dry compact subgrade layer above the septum will vary in different soils and in different localities and climates. The septum, 2, may be located either adjacent to or below the normal frost line, if considered necessary, or in many cases, it may be located above the frost line without endangering the stability of the road.

While it is not believed that it will be necessary in most instances to provide more than a single septum below a single strata of the sub-grade soil, my invention includes the provision of a plurality of septums at different distances from the upper surface of the subgrade, if this is necessary or desirable, and in Fig. 3 I have shown a slight modification of my invention in which the parts corresponding to those shown in Figs. 1 and 2 are given the same reference numerals with the addition of 100.

In this instance the surface earth is excavated to a greater depth than heretofore described, to wit, to a level indicated by the dotted line, $y-y$. The lateral drainage ditches, 103, are carried to a greater depth so that the water level therein will be below the level of the dotted line represented by $y-y$. The entire surface between the ditches is then provided with an impervious septum, indicated at 102^a, in any of the ways previously described. A portion of the dry subgrade soil, indicated at 104^b,

is then placed on top of the septum, 192^a, to any desired depth and compacted in any usual or well known manner. A second septum, indicated at 102, is then provided above the layer 5 of dry subgrade material, 104^b, extending the entire distance between the drainage ditches, and the remaining portion of the subgrade material is applied above the upper septum, 102, and compacted and graded to the desired sub-
10 grade level. The water-proof wearing course, 105, or roadway, is then applied over the top of the subgrade material, 104, and may be of any desired depth and of any desired character, whether merely a water-proof wearing
15 course of bituminous material admixed with earth or broken stone, or any other desired form of pavement may be erected upon the upper layer of subgrade soil, 104. The shoulders, 104^a, may also be protected by water-proof material,
20 as indicated at 105^a, extending downwardly past both of the layers of dry compact subgrade material, 104 and 104^b.

While this embodiment of my invention involves additional expense, it is obvious that it
25 affords a double protection against infiltration by capillary action, as any water from that source would have to pass through both the septums, 102^a and 102, in order to reach the upper course, 104.

30 While my invention is especially adapted to the preparation of subgrade for roads and highways, it will be understood that it may be applied to the preparation of subgrade for any sort of pavement, road, airport runway, taxiway, landing strip or landing field, or in any other connection in which a supporting surface is to be provided. My invention is especially adapted for use in connection with preparation
35 of subgrades for country roads and the like where a cheap and durable roadway is desired and where the enormous cost of cement and other expensive roadways makes it impracticable to divert large sums of money to such purposes.

40 While I have referred to the subgrade material above the septum or septums as being "dry", this does not necessarily mean bone dry, but includes a condition in which the material may have a moderate degree of moisture
45 which will not decrease its load carrying capacity. It will also be understood that should any excess water penetrate into the subgrade material above a septum, it will tend to drain out through the shoulders to the lateral drains, and the waterproof protection for the shoulders, indicated at 5^a and 105^a, where employed may be of such character as to facilitate the passage over them of precipitated water without hermetically sealing the surfaces. The surface
50 over which the septum or septums is or are laid may also be crowned, as indicated for example in Fig. 3, or inclined or otherwise constructed so as to facilitate drainage from the superimposed subgrade material should excess
55 water find access thereto, at any time.

What I claim and desire to secure by Letters Patent is:—

1. The method of forming a supporting bed, which consists in placing an impervious substantially horizontal septum upon the subgrade soil at a predetermined depth below the normal subgrade level, then placing a bed of natural subgrade or soil material susceptible to capillary action on said septum, having its upper surface below the normal subgrade level, placing an impervious substantially horizontal septum upon said bed of natural subgrade or soil material, placing another bed of natural subgrade or soil material susceptible to capillary action upon said second septum, providing drainage adjacent to the lateral margins of said beds of a character to prevent a water level adjacent thereto higher than the first mentioned septum, and applying an impervious wearing surface over said last mentioned bed. 80
90

2. A roadway comprising an impervious septum supported in natural subgrade soil below the normal subgrade level, a substantially dry supporting bed of natural subgrade soil susceptible to capillary action on said septum, an impervious wearing surface mounted on the supporting bed, drainage ditches at the opposite lateral extremities of said septum having a depth sufficient to prevent a water level above said septum, and a protective coating on the walls of said ditches above and adjacent to the septum for preventing lateral infiltration into
105 said bed. 95

3. The method of forming a roadway which consists in placing an impervious substantially horizontal septum upon subgrade soil at a predetermined depth below the normal subgrade
110 level of the road, superimposing upon said septum a layer of untreated natural subgrade soil of sufficient thickness to support the normal traffic loads when in a dry condition and providing said layer with lateral drainage slopes 115 and providing a protective coating upon the upper surface of said layer of untreated soil, said protective coating extending over said lateral drainage slopes to their lines of intersection with the plane of the septum, so as to protect it from water of precipitation and lateral infiltration of water. 120

4. A roadway comprising an impervious septum supported on natural subgrade soil below the normal subgrade level, a substantially dry supporting bed of natural subgrade soil susceptible to capillary action on said septum, an impervious septum supported by said bed below the normal subgrade level, a substantially dry supporting bed of natural subgrade soil susceptible to capillary action on the upper septum, an impervious wearing surface mounted on the upper supporting bed, drainage ditches at the opposite lateral extremities of said septums having a depth sufficient to prevent a water level above the lower of said septums, and a protective coating on the walls of said ditches above and adjacent to the lower septum for preventing lateral infiltration into said beds. 125
